DESIGN FOR A TRAILER

Richard J. Elkus, San Francisco, Calif.

Application December 14, 1942, Serial No. 109,036

Term of patent 7 years

To all whom it may concern:

Be it known that I, Richard J. Elkus, a citizen of the United States, residing in the city and county of San Francisco, State of California, have invented a new, original, and ornamental Design for a Trailer, of which the following is a specification, reference being had to the accompanying drawing, forming part thereof.

Figure 1 is a perspective view of the rear end and one side of the trailer showing my design; and

I claim:

The ornamental design for a trailer, as shown.
RICHARD J. ELKUS.
